SYNTHETIC REVERBERATION SYSTEM

Harry F. Olson, Princeton, N. J., assignor to Radio Corporation of America, a corporation of Delaware

Application June 22, 1946, Serial No. 678,707

11 Claims. (Cl. 179-1)

1

This invention relates to synthetic reverberation systems, and more particularly to an acoustic-electronic reverberation simulator for introducing synthetic reverberation in reproduced sound whereby rendition of the sound may be greatly enhanced.

When a source of sound is started in a room, the energy does not build up instantly due to the finite velocity of propagation of a sound wave. Each pencil of sound sent out by the source is reflected many times from the absorbing walls of the room before it is ultimately dissipated to a level below the ambient or threshold level of the room. A steady state condition obtains when the energy absorbed by the walls equals the energy delivered by the sound source. In the same way, when the source is stopped, some time is required before the energy is absorbed to a level below the ambient or threshold level. The reverberation time has been arbitrarily defined as the time required for the sound to decrease to one-millionth of the original intensity after the source of the sound has been stopped.

It has been established that there exists an optimum reverberation time for a particular room and for a particular type of sound rendition. This means that, for a given room, such as a broadcasting or a recording studio, for example, different reverberation times are required depending upon the type of sound rendition. One of the major problems of sound broadcasting and sound recording has been to control the amount and type of reverberation in the pickup part of the system, or in the recording part of the system, as the case may be, in order to provide sound which, when reproduced, will have the proper amount and quality of reverberation. The reverberation time of studios has been controlled previously, within certain limits, by various means designed to vary the degree of absorption. It has also been proposed to control the reverberation time of the collected sound by the use of directional microphones. However, conditions often exist which necessitate a change in reverberation in a fraction of a second. Obviously, to change the absorption in a studio by means of sliding panels, for example, as has been done heretofore, is a rather cumbersome procedure. Furthermore, very drastic changes in the degree of reverberation are often required as, for example, from one-half second to three seconds.

At the present time, most broadcast and recording studios employ reverberation chambers to vary the amount of reverberation in a reproduced sound program. These reverberation

2

chambers are rooms about the size of the average living room with a reverberation time of about 3 seconds. The sound is fed into the chamber by means of a loudspeaker and is picked up by a microphone. The loudspeaker-room-microphone combination constitutes a reverberation simulator. Among the disadvantages of such a system is that the reverberation time is fixed. Usually, also, the space required for such a studio is another disadvantage, particularly in areas where the rents are high. There are also a number of other disadvantages which characterize reverberation simulators of this type. As substitutes for such reverberation systems or chambers, a number of other systems have been proposed. The latter include disc recordings, electrical delay circuits, magnetic tape recordings with delay, mechanical or spring wire delays, phosphor coated discs, and so on. These systems all possess one or more disadvantages which are too well known to require further comment.

The primary object of my present invention is to provide an improved synthetic reverberation system which is free from the above mentioned and other objections which are found in synthetic reverberation systems proposed heretofore.

More particularly, it is an object of my present invention to provide an improved system for producing synthetic reverberation by means of which the amount and type of reverberation can be controlled over a substantial range to provide optimum reverberation characteristics either for a particular room or studio or for a particular rendition which is to be recorded or broadcast and later reproduced.

Another object of my present invention is to provide an improved synthetic reverberation system as aforesaid which will have a substantially uniform reverberation frequency characteristic and in which the reverberation characteristic can be readily controlled to accentuate either the high or the low frequency reverberation.

Still another object of my present invention is to provide an improved synthetic reverberation system which requires no recordings and therefore is devoid of expensive recording and reproducing mechanisms generally associated therewith.

A further object of my present invention is to provide an improved synthetic reverberation system of the type set forth which can be housed in a compact cabinet structure and which can be placed in a room or studio at any suitable point to provide the reverberation characteristics desired for the particular room and suitable for

the particular program to be either broadcast from or recorded in this room.

It is also an object of my present invention to provide a synthetic reverberation system as above set forth which is very compact in construction, which is readily portable and therefore can be easily transported from one room to another, which is highly efficient in use, and which is quite inexpensive in cost.

In accordance with my present invention, the synthetic reverberation system includes a plurality of delay channels for producing a plurality of echoes of the non-reverberant sound with different phases and mixing the same with the non-reverberant sound. One system constructed in accordance with my present invention included four loudspeaker-pipe-microphone delay systems which provided delays of approximately 23, 50, 68 and 100 milliseconds, the pipes providing the desired delays. The channel with the longest delay is used as part of a controlled, negative feedback network in which the amount of feedback controls the reverberation. The sound in this loop is fed into all four systems again and again. In this way, each second contains 40 components. The fact that my improved system supplies such a large number of components makes the introduced reverberation quite realistic. The reverberation time may be varied from zero to three seconds in a fraction of a second by merely varying the amount of negative feedback. A mixer makes it possible to adjust the ratio of direct to reverberant sound. The components of my improved reverberation simulator can be housed in a compact cabinet and can be placed in any desired location within a particular room.

The novel features of my invention, as well as additional objects and advantages thereof, will better be understood from the following description of two embodiments thereof, when read in connection with the accompanying drawings, in which

Figure 1 is a diagrammatic view illustrating the basic elements of a system for introducing synthetic reverberation in reproduced sound;

Figure 2 is a diagrammatic view of one form of synthetic reverberation producing system in accordance with my present invention;

Figure 3 is an enlarged, partly sectional view of one of the loudspeaker-microphone units with the associated pipe of Fig. 1;

Figure 4 shows, graphically, for a fraction of a second, the decay pattern of the various sound output components of the system of Fig. 2;

Figure 5 is a set of curves showing the average attenuation characteristics of the several pipes shown in the system of Fig. 1;

Figure 6 is a set of curves showing the reverberation time vs. frequency characteristics of the reverberation simulator of Fig. 2 for various settings of the reverberation control; and

Figure 7 shows, diagrammatically, a second form of my improved reverberation simulator.

Before referring more particularly to the drawings, it may be pointed out that, when a source of sound operates in a room, the sound pressure at the microphone or pickup point may be expressed as follows:

$$p = A_1 \cos k(ct - r_1) + A_2 \cos k(ct - r_2) + A_3 \cos k(ct - r_3) + \dots$$

where

A_1 = amplitude of the direct sound at the microphone,

r_1 = distance between the source and the microphone,

c = velocity of sound,

$k = 2\pi/\lambda$,

λ = wavelength,

t = time,

$A_2, A_3, \dots$ = amplitudes of the reflected sound at the microphone,

$r_2, r_3, \dots$ = total distances along various reflection paths between the source of sound and the microphone.

In the above equation, the first term of the right hand member represents the direct sound and all the other terms represent the reflected sound. The amplitude A of the reflected sound decreases with increasing distance r between the sound source and any particular microphone. From the above equation, it will be apparent that the conditions represented thereby may be simulated by a system of the type shown in Figure 1 in which the input provides direct signal or non-reverberant sound representing electrical waves along a channel 1, and delayed signal or reverberant sound representing electrical signals along a plurality of parallel channels 2, 3, 4, 5, 6, 7 and 8. Each of the channels 2 to 8, inclusive, includes a sending transducer 9 coupled to a receiving transducer 10 through a suitable delay system 11, the delay systems 11 each having a different degree of delay. The outputs of the transducers 10 may be supplied through a plurality of ganged attenuators 12 in each of the channels 2 to 8, inclusive, to a mixer 13 which mixes the direct and reverberant sound representing signals and supplies them to a suitable output member. It will also be apparent from the system of Fig. 1 that, to obtain the required conditions in a room, would necessitate a tremendous number of transducers and would, therefore, be impractical. On the other hand, any reduction in the number of units must necessarily involve a compromise. It is desirable to include more components rather than less, particularly for the longer reverberation times.

In the simplified reverberation simulators of my invention as represented in Figures 2 and 7, there are forty components of sound per second. Such systems adequately fill most practical requirements.

Referring, now, to Figure 2, there is shown a microphone or other suitable input member 21 which is adapted to pick up a train of direct or non-reverberant sound waves and to translate them into a corresponding train of non-reverberant sound representing electrical waves. These electrical waves may be fed first through a master gain control 23 and then along two parallel paths 25 and 27, the direct sound representing signals in the path 25 being fed to a variable or adjustable

mixer 29. Non-reverberant sound representing signals supplied by the microphone or the like 21 are fed along the path 27 through one or more attenuators 31 and thence to an amplifier 33. The output of the amplifier 33 may be fed

to one or more amplifiers 35 and thence along parallel branches 37, 39 and 41 through power amplifiers 43, 45 and 47 to four electro-acoustic transmitters or loudspeaker units 51, 53, 55 and 57 each forming part of a channel for producing reverberant sound representing electrical waves or signals.

In the system of Figure 2, four such channels C_1, C_2, C_3, C_4 are shown arranged in parallel. In the channel C_1 , the loudspeaker 51 is connected by an acoustic line 61 to an acousto-electrical

receiver or microphone 71. Similarly, in the channels C₂, C₃ and C₄, the respective loudspeakers 53, 55 and 57 are connected to their associated microphones 73, 75 and 77 by acoustic lines 63, 65 and 67. The acoustic lines 61, 63, 65 and 67 may be constituted of aluminum pipe one inch in diameter, the pipe 67 being approximately 25 feet in length, the pipe 65 being approximately 55 feet in length, the pipe 63 being approximately 75 feet in length and the pipe 61 being approximately 110 feet in length. It will be apparent, therefore, that the non-reverberant acoustic signals or sound waves emitted by the several loudspeakers 51, 53, 55 and 57 will be conducted to their respectively associated microphones 71, 73, 75 and 77 and that such waves will reach the several microphones at a different phase in each channel. Thus, the electrical signals supplied by each of the microphones 71, 73, 75 and 77 to a mixing circuit or network 79 will represent reverberant sounds or echo effects of different phases. The network 79 may be of the type shown in the U. S. patents to Ballard 2,192,959, or Parisier 2,403,232, for example. Reverberant sound representing electrical waves or signals are supplied by the mixing network 79 through an amplifier 81 to the mixer 29 where the direct and the reverberant sound representing electrical waves are mixed in the desired proportion. The signals supplied by the mixer 29 may be amplified by suitable amplifiers 83 and 85 and supplied to a suitable output member 89, such as a loudspeaker or the like.

The several loudspeakers 51, 53, 55 and 57 and the several microphones 71, 73, 75 and 77 may be either identical in type and construction or of different types and constructions, as may be found most suitable. Figure 3 illustrates one such unit which may be used either as a loudspeaker or a microphone. This unit is a dynamic unit having a magnetic yoke 91 which supports, centrally, a magnetic polepiece 93 and a magnetic yoke plate 95 which has a suitable opening at the center to provide an air-gap 97 in a well known manner. Within the air-gap 97 is a voice coil 99 carried by a diaphragm 101 flexibly supported for vibration by a centering spider 103, also in well known manner. The unit includes an throat 105 which is connected to its associated pipe (for example, the pipe 61) by a conical connector 61a which may or may not be an integral part of the pipe, as may be found most suitable. The pipes 61, 63, 65 and 67 may be one inch diameter aluminum pipe having a wall thickness of approximately one-thirty-second inch. As mentioned heretofore, the pipe 67 has a length of the order of 25 feet, the pipe 65 has a length of the order of 55 feet, the pipe 63 has a length of the order of 75 feet, and the longest pipe 61 has a length of the order of 110 feet. Pipes of these lengths will introduce in the channels C₄, C₃, C₂, C₁ time delays of the order of 23, 50, 68, and 100 milliseconds, respectively. The conical or tapered pipe portions, such as the portion 61a, may be approximately 48 inches in length. The attenuation characteristics of the four pipes 61, 63, 65, 67, as described above, are shown in Figure 5. If desired, suitable equalizers may be employed between the input and the output of the amplifier system 35, 43, 45, 47 to compensate for the greater attenuation at the higher frequencies in the several pipes 61, 63, 65 and 67.

It will be apparent from the foregoing description, that the electrical waves or signals supplied by the microphone units 71, 73, 75 and

71 represent reverberant sound of different phases by reason of the different delays provided by the pipes 61, 63, 65 and 67. Since the sound waves emitted by the loudspeakers 51, 53, 55 and 57 are confined to the several pipes, high sound pressures may be obtained with small inputs. This means that the ratio of signal to noise is very large (more than 60 db). Furthermore, the non-linear distortion is low because the loudspeaker units, which are usually the principal source of distortion, operate at a very low level and, therefore, do not produce any appreciable non-linear distortion. The reason for using four delay channels, as shown in Fig. 2, is to obtain 15 sound components which are staggered with respect to time. Suppose, for example, that an impulse of a train of waves enters the system. The output consists of, first, the direct sound impulse; a reverberant sound representing impulse 20 of a phase corresponding to 25 feet later due to the 25 foot pipe 67; another reverberant sound representing impulse of a phase which corresponds to 55 feet later due to the pipe 65; another reverberant sound representing impulse of a 25 phase which corresponds to 75 feet later by reason of the pipe 63; and finally a reverberant sound representing impulse of a phase which corresponds to 110 feet later due to the length of the pipe 61.

The channel C₁, which includes the longest pipe 61, is made part of a negative feedback system by connecting a portion of the output of the mixing network 79 to the amplifiers 35 through a variable reverberation time controlling 35 or feedback controlling device 107 (preferably a step-by-step control) and an amplifier 109. The negative feedback system represented by the dash line 110 in Figure 2 feeds sound into the pipes 63, 65 and 67 as well as back to the pipe 61, 40 so that sound impulses follow of phases corresponding to 135 feet after the original, direct impulse which enters the system, 165 feet later, 185 feet later, 220 feet later, 245 feet later, etc. A part of the components for one second reverberation time is shown in Figure 4. It will be seen that the reverberant sound consists of a large number of components, there being 40 components per second. Such a large number of components would be entirely impractical in a 50 system without feedback, whereas the improved system described above makes this entirely feasible and produces a train of sound which is supplied by the output member 89 with precisely the desired type and amount of reverberation.

The step gain control 107 which controls the amount of feedback may be adjusted to a first position to cause the system to oscillate. The succeeding positions of the gain control 107 may be such as to set the reverberation time for three 60 seconds, two seconds, one second, and then one-half second. A system such as described above can be housed very nicely in a relatively small cabinet with the operating knob of the gain control 107 mounted at some convenient place on one wall of the cabinet. In one construction, the entire system including the delay pipes, loudspeakers, microphones, amplifiers, mixers, regulated power supply, etc., was housed in a cabinet 36 inches wide, 24 inches deep and 78 inches high.

The measured reverberation times of this particular construction for various settings of the gain control 107 is shown in Figure 6. It will be noted, from this figure, that the reverberation time for one-half, one and two seconds is quite uniform with respect to frequency. The lower

reverberation time at the higher frequencies is about the same as that obtained in a room. The reverberation time with respect to frequency is not quite as uniform for the three second setting of the gain control 107. This is due to the fact that, for this setting, small variations in amplifiers have a great effect. However, neither is the reverberation time of a room using a single loudspeaker and microphone uniform with respect to frequency. Hence, the variation in reverberation time with frequency at the three second setting is not serious. If desired, the reverberation time vs. frequency characteristic can be changed to give greater reverberation at either the lower or the higher frequencies. For the characteristics of Figure 6, the amplifiers were adjusted to give the same reverberation time for the frequency range from about 100 to about 2000 cycles per second.

In Figure 7, there is shown a modified form of my improved synthetic reverberation producing system. It will be noted that, in this system, a single loudspeaker unit 51 is employed. This reduces the number of power amplifiers required. In place of the pipes 63, 65 and 67, small bleeder pipes 63a, 65a and 67a, which are tapped off from the pipe 61 at suitable points spaced along the length thereof, are used to feed the microphone units 71, 73, 75 and 77, respectively. The pipe 61 may again be a 110 foot, one-inch diameter, aluminum pipe, and the pipes 63a, 65a and 67a, which may be one-quarter inch diameter, aluminum pipes, are tapped off from the 110 foot pipe 61 at such points as to provide a 75 foot path through the pipe 63a, a 55 foot path through the pipe 65a, and a 25-foot path through the pipe 67a. By selecting the proper tapping points on the pipe 61, the response frequency characteristic of all the microphone units 71, 73, 75 and 77 will be substantially the same. A fixed attenuator 111 may be provided between the two one-stage amplifiers represented by the blocks 35 for changing the shapes of the reverberation time vs. frequency characteristic curves for the purpose either of obtaining a uniform reverberation frequency characteristic, or of accentuating either the high or low frequency reverberation. The direct and reverberant sound mixer 29 of Figure 2 is omitted in the modification of Figure 7 since it is of little or no value in standard broadcast practice. The simplified synthetic reverberation producing system of Figure 7 can be used as an adjunct in the same way that reverberation chambers are now used. With the simplifications shown in Figure 7, the number of vacuum tubes required is greatly reduced, as is also the amount of one-inch pipe required for the delays. With these changes, the unit can be housed in a portable cabinet of about 40 inches by 34 inches by 18 inches.

From the foregoing description, it will be apparent that I have provided an improved synthetic reverberation simulator which is simple in construction and which can be used in any surroundings for the indicated purpose. Although I have shown two modifications of my invention, it will undoubtedly be apparent to those skilled in the art that many variations thereof, as well as changes in the particular forms herein described, may be made within the spirit of my invention. I therefore desire to have it understood that the forms of my invention described above are merely for the purpose of illustration and are not to be taken as limiting.

I claim as my invention:

1. In a synthetic sound reverberation producing system, means for translating non-reverberant sound waves into non-reverberant sound representing electrical signal waves, a plurality of sound wave conveying channels for producing reverberant sound representing electrical signal waves, each of said channels including an electro-acoustical transmitter, an acousto-electrical receiver, and an acoustic delay line connecting said transmitter to said receiver for conducting to said receiver the sound waves emitted by said transmitter, signal wave conveying means coupling said first named means to each of said transmitters to apply said first named signal wave thereto, a signal wave mixing network connected to said receivers for combining the reverberant sound representing signal wave output thereof, electrical coupling means including said mixing network and a portion of said signal wave conveying means providing a feedback path between said receivers and transmitters for a portion of the combined reverberant sound representing electrical signal waves from said receivers, and gain controlling means for said electrical coupling means for controlling the degree of feedback of said last named signal waves and the reverberation time of the system.

2. In a synthetic sound reverberation producing system, means for translating non-reverberant sound waves into non-reverberant sound representing electrical signal waves, a plurality of sound wave conveying channels for producing reverberant sound representing electrical signal waves, each of said channels including an electro-acoustical transmitter, an acousto-electrical receiver, and an acoustic delay line connecting said transmitter to said receiver for conducting to said receiver the sound waves emitted by said transmitter, the acoustic lines of said channels being each of different length whereby to provide an acoustic delay of different magnitude in each of said channels, signal wave amplifier means coupling said first named means to each of said transmitters to apply said first named signal waves thereto, a signal wave mixing network connected to said receivers for combining the reverberant sound representing signal wave output thereof, electrical coupling means including said mixing network and a portion of said signal wave conveying means providing a feedback path between said receivers and transmitters for a portion of the combined reverberant sound representing electrical signal waves from said receivers, and gain controlling means for said electrical coupling means for controlling the degree of feedback of said last named signal waves and the reverberation time of the system.

3. A synthetic reverberation producing system according to claim 2 characterized in that said feedback path is a negative feedback path.

4. A synthetic reverberation producing system according to claim 2 wherein there are four of said channels, the acoustic lines of said channels being, respectively, of the order of 25 feet, 55 feet, 75 feet and 110 feet in length.

5. A synthetic reverberation producing system according to claim 2 wherein said longest acoustic line has portions common to the others of said lines, and wherein the remainder of each of said other lines is constituted by bleeder lines connected to said longest line at spaced points therealong.

75. 6. In a synthetic reverberation producing sys-

tem, means for translating non-reverberant sound waves into non-reverberant sound waves representing electrical waves, a plurality of sound wave conveying channels for producing reverberant sound representing electrical signal waves, each of said channels including an electro-acoustical transmitter, an acousto-electrical receiver, and an acoustic delay line connecting said transmitter to said receiver for conducting to said receiver sound waves emitted by said transmitter, signal wave conveying means for applying to each of said transmitters non-reverberant sound representing electrical signal waves derived from said first named means, said channels serving to convert the waves applied to their respective transmitters into reverberant sound representing electrical signal waves, a mixing network connected to said receivers for combining the reverberant sound representing electrical signal waves supplied by said receivers, means including at least one of said channels arranged to provide a negative feedback path between said receivers and transmitters through said mixing circuit and at least a part of said signal wave conveying means, and output circuit means for combining non-reverberant sound representing electrical signal waves derived from said first named means with reverberant sound representing electrical signal waves derived from said mixing circuit.

7. A synthetic reverberation producing system according to claim 6 characterized in that the acoustic lines of said channels are all of different length whereby to provide an acoustical delay of different magnitude in each of said channels to produce echo simulating effects of different phases.

8. A synthetic reverberation producing system

according to claim 6 characterized in that the acoustic lines of said channels are all of different length whereby to provide an acoustical delay of different magnitude in each of said channels to thereby produce echo simulating effects of different phases, and characterized further in that at least the channel having the longest one of said acoustic lines is included in said feedback path.

9. A synthetic reverberation producing system according to claim 6 characterized by the addition in said feedback path of means for controlling the amount of feedback in said path and the reverberation time of the system.

10. A synthetic reverberation producing system according to claim 6 characterized in that said combining means comprises a variable mixer.

11. In a synthetic reverberation producing system the combination according to claim 6, characterized by the addition of means for selectively controlling the relative amounts of reverberant and non-reverberant sound representing electrical signal waves delivered to said output circuit means.
